UNITED STATES PATENT OFFICE

WILLIAM M. BLECKER, OF CANTON, OHIO, ASSIGNOR OF FIFTY-ONE PER CENT TO
EDWARD A. LANGENBACH, OF CANTON, OHIO

CONTINUOUS STRIP AND SHEET MILL

Application filed August 16, 1927. Serial No. 213,317.

The invention relates to the continuous rolling of strips and sheets and the object of the improvement is to provide an apparatus in which slabs from a blooming mill and the like may be continuously rolled into cold rolled strips, hot rolled and annealed strips or sheets, as desired, means being provided for shearing the edges and ends of the sheets as they are passed through the apparatus.

10 An embodiment of the invention is illustrated in the accompanying drawings, in which

Figures 1, 1^a and 1^b are a complete plan view with parts broken away of the apparatus by which sheets, cold rolled strips or hot rolled and annealed strips may be rolled from slabs in a continuous operation;

15 Figs. 2, 2^a and 2^b are vertical sectional views through the apparatus showing the mechanism for rolling cold rolled strips from the slabs; and

20 Figs. 3 and 3^a are vertical sectional views showing the apparatus for continuous rolling of sheets.

25 Similar numerals refer to similar parts throughout the drawings.

A blooming mill or the like is indicated generally at 1, a roller conveyor shown at 2 being provided for carrying slabs or the like 30 to and from the mill.

The slabs may be sheared to the desired size as by the shears 3 located beyond the conveyor 2. As each slab is sheared it passes to a slab turning table 4, which may be rotated by any suitable and well known means to turn the slab to the desired position before passing on to the conveyor 5 which carries the slabs through the continuous heating furnace 6.

40 Beyond the continuous heating furnace is located a series of stands of strip rolling mills shown at 7, 8, 9, 10 and 11, each stand being spaced further from the preceding stand than the next preceding stand of rolls in order to

5 compensate for the continuous elongation of the strip as it passes through the successive stands of rolls.

Conveyors 12 are located between the several stands of strip rolling mills for the purpose of continuously carrying the strip

through the several stands. A conveyor 13 is located beyond the last stand of strip rolling mills 11 and is associated with a transfer table 14, which may carry the strips to one side of the conveyor and a similar transfer table 15 arranged to carry the strips to the other side thereof.

55 Side rolls 7^a, 8^a, 9^a and 10^a are located centrally between the stands of mills 7, 8, 9, 10 and 11, for the purpose of rolling the edges of the strip passing through said mills.

60 Beyond the transfer table the conveyor 13 passes through the cooler 16 provided with inlet and outlet pipes 17 and 18 respectively, through which cold air or the like may be passed to the strips for the purpose of cooling the strips to a pickling temperature.

65 A pair of feed rolls 19 may be located directly beyond the cooler for passing the strips through a continuous pickling tank 20, preferably formed of acid resisting steel. The strips are adapted to be passed down through the pickling solution by means of the guides 21 located in the pickling tank.

70 The cover 22 of the pickling tank may be connected as by the pipe 23 with a suction fan 24 adapted to carry the fumes from the pickling bath and discharge them at any point outside of the room as through the discharge pipe 25.

75 Pinch rolls 26 may be located beyond the pickling tank for the purpose of discharging the pickled strips therefrom and passing them through the washing tank 26^a after which they pass on to the conveyor 27, which extends through a drying furnace 28 and on beyond to an edge trimmer 29, and thence to a series of stands of cold rolling mills 30.

80 A shear 15^a may be located somewhere in the apparatus between the hot mills and the cold rolling mills to shear the front end of the hot strip before the same enters the cold rolling mills.

85 Beyond the cold rolling mills the conveyor is arranged to carry the strips through a non-oxidizing annealing furnace 31 and then if desired the strips may be passed through a roller leveler as shown at 32 and disposed of in any desirable manner.

90 By passing the strips straight through the 100

apparatus above described cold rolled annealed strips are produced in a single continuous operation from the slabs.

If it is desired to roll hot rolled annealed strips, the process is as above described until the strips reach the conveyor 13, at which time the transfer table 14 is operated to move the strips laterally on to the conveyor 33 where they are passed around the cooler 16, pickling tank 20, washing tank 26^a, drying furnace 28, and cold rolling mills 30. As the strips reach the transfer table 34 they may be moved back to the conveyor 27 and then passed through the annealing furnace 31 and roller leveler 32.

It should be understood that instead of transferring the strips back by means of the transfer table 34 they may be passed straight ahead through a duplicate of the annealing furnace 31, and then through a roller leveler if desired.

If it is desired to roll sheets the process is the same as above described until the strips reach the conveyor 13, at which time they are transferred to the left by the transfer table 15 and deposited upon a conveyor 35 where they are sheared as by the shears 36 to the proper length for rolling sheets and then piled in piles of two or more sheets upon the matching table 37, the piles being then carried by the conveyor 38 through the continuous sheet furnace 39 and then through the successive stands of sheet rolling mills 40, 41, 42, 43 and 44.

These stands of sheet rolling mills are successively spaced at increasing distances from each other to compensate for the elongation of the piles of sheets passing therethrough.

For the purpose of removing scale from the sheet packs as they pass through these mills, angularly disposed steam jets 45 may be directed across the surfaces of the packs.

The packs of sheets may then be passed through the edge trimming shears 46 and then sheared to length by the end trimming shears 47 and carried away from the shears as by the conveyor 48.

From the above it will be obvious that the slabs from the blooming mill may be continuously passed through the apparatus to produce either cold rolled or hot rolled and annealed strips or sheets, as desired.

The strips may be rolled to the desired gauge by using either the hot rolling process as required, or the sheets may be rolled to the desired gauge by piling the necessary sheets in a pack before passing through the continuous sheet mills.

I claim:

60 1. An apparatus for continuous and simultaneous, selective rolling of sheets, cold rolled strips and hot rolled and annealed strips from slabs and the like, including a blooming mill, slab shears, a slab turning table, a heating furnace, a plurality of stands of strip rolling mills, an annealing furnace, a matching table, a continuous sheet furnace, continuous sheet

70 mills, a continuous pickling tank, a drying furnace, a plurality of stands of cold rolling mills, an annealing furnace, means for passing the material continuously through said apparatus, and means for passing the material around the pickling tank, drying furnace and cold rolling mills.

2. An apparatus for continuous and simultaneous, selective rolling of sheets, cold rolled strips and hot rolled and annealed strips from slabs and the like, including a blooming mill, slab shears, a slab turning table, a heating furnace, a plurality of stands of strip rolling mills, a continuous pickling tank, a drying furnace, a plurality of stands of cold rolling mills, and an annealing furnace, a matching table, a continuous sheet furnace, continuous sheet rolling mills, and means for selectively passing the material through the pickling tank, drying furnace, cold rolling mills and annealing furnace, or through the matching table, continuous sheet furnace and sheet rolling mills.

3. An apparatus for continuous and simultaneous, selective rolling of sheets, cold rolled strips and hot rolled and annealed strips from slabs and the like, including a blooming mill, slab shears, a slab turning table, a heating furnace, a plurality of stands of strip rolling mills, a continuous pickling tank, a drying furnace, a plurality of stands of cold rolling mills, an annealing furnace, a matching table, a continuous sheet furnace, steam jets for removing scale from the material, continuous sheet rolling mills, and means for selectively passing the material through the pickling tank, drying furnace, cold rolling mills and annealing furnace, or through the matching table, continuous sheet furnace and sheet rolling mills.

4. An apparatus for continuous and simultaneous, selective rolling of sheets, cold rolled strips and hot rolled and annealed strips from slabs and the like, including a blooming mill, slab shears, a slab turning table, a heating furnace, a plurality of stands of strip rolling mills, a continuous pickling tank, means for withdrawing fumes from the pickling tank, a drying furnace, a plurality of stands of cold rolling mills, an annealing furnace, means for passing the material continuously through said apparatus and means for passing the material around the pickling tank, drying furnace and cold rolling mills.

5. An apparatus for continuous and simultaneous, selective rolling of sheets, cold rolled strips and hot rolled and annealed strips from slabs and the like, including a blooming mill, slab shears, a slab turning table, a heating furnace, a plurality of stands of strip rolling mills, a continuous pickling tank, a drying furnace, a plurality of stands of cold rolling mills, an annealing furnace, a matching table, a continuous sheet furnace, continuous sheet

5 rolling mills, means for trimming the edges and ends of the sheets, and means for selectively passing the material through the pickling tank, drying furnace, cold rolling mills and annealing furnace, or through the matching table, continuous sheet furnace and sheet rolling mills.

6. An apparatus for continuous and simultaneous, selective rolling of sheets, cold rolled 10 strips and hot rolled and annealed strips from slabs and the like, including a blooming mill, slab shears, a slab turning table, a heating furnace, a plurality of stands of strip rolling mills, a conveyor beyond the strip rolling 15 mills, a transfer table upon each side of the conveyor, a pickling tank beyond the conveyor, a drying furnace, a plurality of stands of cold rolling mills, an annealing furnace, a second conveyor communicating with one of 20 the transfer tables and with the annealing furnace, a matching table communicating with the other transfer table, a continuous sheet furnace beyond the matching table, a plurality of stands of sheet rolling mills beyond 25 the continuous sheet furnace, and means for passing material directly over said first named conveyor or over either of the transfer tables and the apparatus communicating therewith.

7. An apparatus for continuous and simultaneous, selective rolling of sheets, cold rolled strips and hot rolled and annealed strips from slabs and the like, including a blooming mill, slab shears, a slab turning table, a heating 35 furnace, a plurality of stands of strip rolling mills, a cooler, a continuous pickling tank, a washing tank, a drying furnace, a plurality of stands of cold rolling mills, an annealing furnace, means for passing material continuously 40ously through said apparatus, and means for passing material around the cooler, pickling tank, washing tank, drying furnace and cold rolling mills.

8. An apparatus for continuous and simultaneous, selective rolling of sheets, cold rolled strips and hot rolled annealed strips from slabs and the like, including a blooming mill, slab shears, a slab turning table, a heating furnace, a plurality of stands of strip rolling 50 mills, a cooler, a continuous pickling tank, a washing tank, a drying furnace, a plurality of stands of cold rolling mills, an annealing furnace, a matching table, a continuous sheet furnace, continuous sheet rolling mills, and means for selectively passing material through the cooler, pickling tank, washing tank, drying furnace, cold rolling mills and annealing furnace, or through the matching table, continuous sheet furnace and sheet rolling 55 mills.

9. Apparatus for continuous and simultaneous, selective rolling of sheets, cold rolled strips and hot rolled and annealed strips from slabs and the like, including a blooming 60 mill, slab shears, a slab turning table, a heat-

ing furnace, a plurality of stands of strip rolling mills, a cooler, a continuous pickling tank, a washing tank, a drying furnace, a plurality of stands of cold rolling mills, an annealing furnace, a matching table, a continuous sheet furnace, steam jets for removing scale from the material, continuous sheet rolling mills, and means for selectively passing the material through the cooler, pickling tank, washing tank, drying furnace, cold rolling mills and annealing furnace, or through the matching table, continuous sheet furnace and sheet rolling mills.

10. An apparatus for continuous and simultaneous, selective rolling of sheets, cold rolled strips and hot rolled and annealed strips from slabs and the like, including a blooming mill, slab shears, a slab turning table, a heating furnace, a plurality of stands of strip rolling mills, a cooler, a continuous pickling tank, a washing tank, means for withdrawing fumes from the pickling tank, a drying furnace, a plurality of stands of cold rolling mills, an annealing furnace, means for passing material continuously through said apparatus, and means for passing material around the cooler, pickling tank, washing tank, drying furnace and cold rolling mills.

11. An apparatus for continuous and simultaneous, selective rolling of sheets, cold rolled strips, and hot rolled and annealed strips from slabs and the like, including a blooming mill, slab shears, a slab turning table, a heating furnace, a plurality of stands of strip rolling mills, a cooler, a continuous pickling tank, a washing tank, a drying furnace, a plurality of stands of cold rolling mills, an annealing furnace, a matching table, a continuous sheet furnace, continuous sheet rolling mills, means for trimming the edges and ends of the sheets, and means for selectively passing the material through the cooler, pickling tank, washing tank, drying furnace, cold rolling mills and annealing furnace, or through the matching table, continuous sheet furnace and sheet rolling mills.

12. An apparatus for continuous and simultaneous, selective rolling of sheets, cold rolled strips and hot rolled and annealed strips from slabs and the like, including a blooming mill, slab shears, a slab turning table, a heating furnace, a plurality of stands of strip rolling mills, a conveyor beyond the strip rolling mills, a transfer table upon each side of the conveyor, a cooler beyond the conveyor, a pickling tank beyond the cooler, a drying furnace, a plurality of stands of cold rolling mills, an annealing furnace, a second conveyor communicating with one of the transfer tables and with the annealing furnace, a matching table communicating with the other transfer table, a continuous sheet furnace beyond the matching table, a plurality of stands of sheet rolling mills beyond

the continuous sheet furnace, and means for passing material directly over said first named conveyor or over either of said transfer tables and the apparatus communicating therewith.

5 In testimony that I claim the above, I have hereunto subscribed my name.

WILLIAM M. BLECKER.
